(54) **WELLS, COVERS OF**

(76) Inventor: **Levi Kidder**

*See Middle
Sellers Paley*
The Schedule referred to in those Sellers' Blot and making part
of the same containing a description in the words of the said Mr.
Middleton of his improvement in the application of hy-
draulic cement to securing walls.

The invention which he calls the *art of Seisen* is formed in four parts, which for the sake of description he calls, 1st the wall which is circular and of any desired diameter required for strength and for being built very height aften, and as it were a continuation of the stone wall already raised to certain height and in the ordinary way. 2nd The arch with a circular aperture or other shape in the centre large enough to admit a furnace, and a passage passes through by its sides, the arch rests upon the top of the wall. 3rd The neck which a ring about four inches thick, hath been makes high and of the same diameter as the aperture above mentioned, around which resting on the arch it is coulred

is layer of coarse mortar first prepared for this use, thus forming the first section of the wall about four inches thick and five inches high or of other dimensions if requisite an excavation, which down the earth is, shouldered round firmly bounded, filling the space between this section of the wall and the sides of the well pit. In the same way is prepared another section of the wall uniting with the first, and the earth as before thrown in and packed. In this manner the operation is continued till the wall is raised to the top of the mould when it is complete. The pump if not before should now be introduced and fixed perpendicular in the centre, after which the mould should be removed and a stage suspended by ropes resting on the first mentioned stage should be thrown across the well, around the pump within about two inches of the top of the coarse wall, on this stage a mound of earth is created and firmly packed in the form of an arch or dome, with an elevation in the centre around the pump of about eighteen inches above the top, and within the interior distance of the cement wall. This earth ~~in~~ dome forms the mould for the second part the arch. On the top of this mould is placed centrally in a horizontal position around the pump a ring of sheet iron or other material, about twenty two inches wide and twenty four inches in diameter, made removable. This ring from the aperture into the well, and at the same time the inside mould for the third part or neck which may be of any other shape if desired. This ring being fixed the second part or arch is cast upon the mould about four inches thick or thicker if required and extending from the sides of the ring all over the mould and to the exterior of the wall, upon the top of which when the mould is removed it will rest. Another similar ring is now placed horizontally upon the arch outside of the first ring and parallel with it at the distance of three or four inches. These rings are placed from the mould in which is eas-

The neck of which they determine the dimensions. The neck is cast by filling the space between the rings with the cement mortar uniting with the neck just formed. This are made the first three parts which are now united monolith. To form the cover fill up the space around the pump between it and the first mentioned ring with earth which rises in the form of a neck or dome elevated about six inches above the top of the neck. This constitutes the mould for the cover. Now lay upon the top of the neck a covering of thick rapping paper or other material to form a separation between the neck and cover, and in order to have the cover in two parts insert perpendicular to the mould on opposite sides of the pump two strips or pieces of sheet iron extending from the pump to the exterior of the neck with their upper edges arched and as much above the mould say three inches as the thickness of the cover is to be. This done cast the cover extending from the pump to which it is moulded to the exterior of the neck upon which it is to fit and rest uniting as you advance it place suitable metallic fasteners and handles for the purpose of fastening or removing the cover at pleasure.

The well receiver is now formed and time being allowed for the cement sufficiently to set or harden, the earth may be thrown upon the neck and against the neck level with the surface of the surrounding ground. The cover which with about six inches of the neck is above the ground may now be taken off and the moulds and the stages from the inside removed, after which replace and fasten the cover and you have completed the well receiver, a perfect defence against the on flow of water and the depredations of vermin.

The principle of this improvement consists in the construction in hydraulic cement of a protecting cover and sides to wells custom recessing, and other vessels in the

earth whereby the water within them will be secured against the
influx of surface water and the intrusion of waves in the
mode and by the means substantially as above described
